COMBINED CORNUCOPIA AND CANDLEHOLDER

Gilbert Josephson, White Plains, N.Y.

Application January 8, 1958, Serial No. 49,174

Term of patent 14 years

(Cl. D48—2)

Fig. 1 is a perspective view of a combined cornucopia and candleholder, showing my new design;

Fig. 2 is a top plan view thereof on a reduced scale;

Fig. 3 is a bottom plan view thereof;

Fig. 4 is a front elevational view thereof; and

Fig. 5 is a rear elevational view thereof.

I claim:

The ornamental design for a combined cornucopia and candleholder, substantially as shown.
